US0D1103580S

(12) United States Design Patent (10) Patent No.: US D1,103,580 S
Heckendorn et al. (45) Date of Patent: * Dec. 2, 2025

(54) MESH CAP

(71) Applicants: Thomas Chase Heckendorn, Dallas, TX (US); Brynn Marie Heckendorn, Dallas, TX (US)

(72) Inventors: Thomas Chase Heckendorn, Dallas, TX (US); Brynn Marie Heckendorn, Dallas, TX (US)

(73) Assignee: Shout it Events, LLC, Dallas, TX (US)

() Term: 15 Years

(21) Appl. No.: 29/925,323

(22) Filed: Jan. 24, 2024

(51) LOC (15) Cl. 02-03

(52) U.S. Cl.

USPC D2/882

(57) CLAIM

The ornamental design for a mesh cap, as shown and described.

DESCRIPTION

FIG. 1 is a front top right side perspective view for a mesh cap, showing our new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top plan view of FIG. 1 thereof; and,

FIG. 7 is a bottom plan view of FIG. 1 thereof.

The broken lines in the figures represent stitching, and are part of the claimed design.

1 Claim, 7 Drawing Sheets
